Peterson, San Leandro, Calif.

Application April 28, 1944, Serial No. 113,399

Term of patent 3½ years

(Cl. D55—1)

To all whom it may concern:

Be it known that we, Oscar R. Peterson and Robert A. Peterson, citizens of the United States, residing at the city of Oakland, county of Alameda, and city of San Leandro, county of Alameda, State of California, respectively, have invented a new, original, and ornamental Design for Power Units, of which the following is a specification, reference being had to the accompanying drawing, forming part thereof.

In the drawing:

Fig. 1 is a view in perspective of a power unit showing our design;

Fig. 2 is a top plan view of the same; and

Fig. 3 is an end view of showing the end not shown in Fig. 1.

We claim:

The ornamental design for a power unit, as shown.

OSCAR R. PETERSON.
ROBERT A. PETERSON.
